UNITED STATES PATENT OFFICE.

HENRY TEXTOR, OF BROOKLYN, NEW YORK, ASSIGNOR TO J. S. AND G. F. SIMPSON, OF SAME PLACE.

DESIGN FOR A NEWEL-POST.

SPECIFICATION forming part of Design No. 12,026, dated November 9, 1880.

Application filed August 28, 1880. Term of patent 7 years.

To all whom it may concern:

Be it known that I, HENRY TEXTOR, of the city of Brooklyn, in the county of Kings and State of New York, have originated and produced a new and Improved Design for Newel-Posts, of which the following is a specification.

The character of my design is clearly illustrated in the accompanying drawing, which 10 represents a perspective view of a newel-post embodying my design.

The base A comprises a polygonal or rectangular portion, *a*, having flat sides, above which are convex and concave moldings *b c*, 15 surmounted by a fillet, *d*. The moldings *b c* are interrupted upon each side by a semicircular projection, *e*, extending out flush with the flat side *a*, and in such projection and flat side is a sunken rosette, *f*. Above the base is an outwardly rounded or convex portion, *g*, the surface of which is striated, as clearly shown, and above this portion, and separated from it only by a fillet, *h*, is a concave or hollow portion, *i*, the sides of which are fluted or grooved at. 25 *j*. Above the portion *i* is a band-molding, *k*, interrupted upon each side by a circular raised panel, *k'*, in which is a rose or rosette, *k''*.

The body portion B of the post tapers slightly and has plain sides or faces, save at the top, 30 where is a small scrolled ornament, *l*. Above the body portion B is a bead, *m*, and above this bead upon each face or side is a series of small roses or rosettes, *n*.

The cap C of the post is composed of the fillet 35 *o*, the convex molding *p*, and the fillet *q*, above which and upon each face of the post is a gable-like projection, *r*, the upper outline of which curves downwardly upon each side of the center, and in the face of which is a recessed or 40 sunken scrolled ornament, *s*.

Above the projections *r* is a foliated molding, *t*, of novel form, which is surmounted by a fillet, *u*, and above said fillet the cap slants inward, and is surmounted by an ornamental 45 finial, *v*.

What I claim as my invention, and desire to secure by Letters Patent, is—

1. A design for the base of a newel-post,

consisting of the polygonal or rectangular flat-sided portion *a*, the semicircular projections *e*, 50 and the sunken roses or rosettes *f*, as specified.

2. A design for the base of a newel-post, consisting of the polygonal or rectangular flat-sided portion *a*, the moldings *b c d*, the semicircular projections *e*, interrupting the moldings, and the sunken roses or rosettes *f*, as specified. 55

3. A design for the base and lower portion of a newel-post, consisting of the polygonal or 60 rectangular flat-sided portion *a*, the moldings *b c d*, the rounded or convex portion *g*, having a striated surface and the concave or hollow portion *i*, having a fluted or grooved surface, 65 as specified.

4. A design for the base and lower portion of a newel-post, consisting of the polygonal or rectangular flat-sided portion *a*, the moldings *b c d*, the convex or rounded portion *g*, the 70 surmounting concave portion *i*, the band-molding *k*, the circular raised panels *k'*, and the roses or rosettes *k''*, as specified. 75

5. A design for the upper portion of a newel-post, consisting of the scrolled ornaments *l* and the bead *m*, the roses or rosettes *n* upon 75 each side, as specified.

6. A design for the cap of a newel-post, consisting of the gable-like projections *r*, having rounded or curved upper outlines, the recessed or sunken scrolled ornaments *s*, the foliated 80 molding *t*, and the fillet *u*, as specified.

7. A design for a newel-post, consisting of the polygonal or rectangular flat-sided portion *a*, moldings *b c d*, the projections *e*, the sunken roses or rosettes *f*, the rounded or convex portion *g*, the concave portion *i*, the circular raised panels *k'*, the roses or rosettes *k''*, the scrolled ornaments *l*, the bead *m*, the roses or rosettes *n*, moldings *o p q*, projections *r*, having recessed scrolled ornaments *s*, and the foliated 90 molding *t*, as specified. 85
